CLAIM

The ornamental design for a front loading appliance, as shown and described.

DESCRIPTION

FIG. 1 is a perspective view of the front loading appliance; FIG. 2 is another perspective view of the front loading appliance;

FIG. 3 is a front view of the front loading appliance;

FIG. 4 is a side view of the front loading appliance; and, FIG. 5 is a top view of the front loading appliance.

The broken lines shown in the figures are for the purpose of illustrating portions of the front loading appliance and form no part of the claims design.

1 Claim, 5 Drawing Sheets(56)
